UNITED STATES PATENT OFFICE.

HOWARD M. BRYCE, OF NEW YORK, N. Y., ASSIGNOR TO A. A. VANTINE & CO., OF SAME PLACE.

DESIGN FOR FABRIC.

SPECIFICATION forming part of Design No. 28,676, dated May 17, 1898.

Application filed February 21, 1898. Serial No. 671,214. Term of patent 3½ years.

To all whom it may concern:

Be it known that I, HOWARD M. BRYCE, a citizen of the United States, residing at Brooklyn, in the city of New York, State of New York, have invented and produced a new and original Design for a Woven Fabric, of which the following is a specification, reference being had to the accompanying drawing, forming part thereof, in which is represented a plan view of a piece of fabric embodying my design.

The leading features of my design consist of a series of irregular shaded lines and spots

running from A to B. The shading is carried out entirely perpendicular, running from C to D. The whole has an appearance of frozen-ice pendants, and the entire design carries out the idea of a Chinese double-water effect.

I claim—

The design for fabric substantially as herein shown and described.

HOWARD M. BRYCE.
